UNITED STATES PATENT OFFICE

2,578,538

COMBINATION SALT AND PEPPER SHAKER
WITH CONCENTRICALLY ARRANGED
COMPARTMENTS

Robert C. Gray, Portland, Oreg.

Application August 7, 1946, Serial No. 688,821

1 Claim. (Cl. 222—142.5)

1
This invention relates to improvements in condiment dispensing devices and more especially to salt and pepper shakers of the type shown and described in my abandoned application Serial No. 581,879, filed March 7, 1945, and entitled Condiment Dispenser.

One of the principal objects of the present invention is to provide an article of this character which is of simple durable and inexpensive construction and which may be manufactured by any of the modern methods of molding or casting and readily assembled into compact form and conveniently operated to dispense the salt or the pepper.

These and other objects will appear as my invention is more fully hereinafter described in the following specification, illustrated in the accompanying drawing and finally pointed out in the appended claim.

In the drawing:

Figure 1 is a top plan view of a dispensing device made in accordance with my invention.

Figure 2 is a top plan view of a modified form of the invention.

Figures 3 and 4 are side elevations of Figures 1 and 2, respectively, with fragments broken away and parts in section for convenience of illustration.

Referring now more particularly to the drawing. In Figure 3, reference numeral 1 indicates the main body of the device which is of hollow cylindrical form. The bottom wall 2 of the body member is provided with a centrally located boss 3 which is apertured and threaded as at 4 to receive one end of a shaft 5. The upper end of the shaft is in threaded engagement as at 6 with a boss 7 depending from the top wall of a cap 8 which is seated in the upper end of the body member 1 and held in place by the shaft 5. The top wall 9 of the cap is formed with a concentric ring 10 which forms a seat and also a seal for the upper end of a cylinder 11 which constitutes the chamber for the pepper. The lower end of the cylinder fits securely over the boss 3 to seal the pepper chamber from the area between said chamber and the wall of the main body member which constitutes the salt chamber 12.

To the top wall 9 of the cap I pivotally mount, as at 13 by means of an upwardly extending boss 13A, a disc 14 formed with a flange 15 which surrounds the upper portion of the cap 8. The disc 14 is provided with a plurality of apertures 15A adapted when rotated to register with apertures 16 in the top wall 9 of the cap 8 for dispensing the pepper.

2

The disc 14 is also provided with apertures 17 which when rotated will register with apertures 18 surrounding the salt chamber for dispensing the salt.

For convenience in aligning and disaligning both series of apertures, I provide a limit stop in the form of a slot 19 formed in the disc 14 and movable with respect to a projection 20 formed on the top 9 of the cap 8. Thus a user has to merely rotate the cap until either end of the limit stop is reached to open or seal off both series of apertures.

In the modified form of the invention shown in Figure 4 the main body member 21, cap 22, disc 23, pepper cylinder 24, pepper dispensing apertures 25 and salt apertures 26, sealing ring 27, and boss 28 are all identical with the corresponding elements shown in Figure 3 except that I eliminate the shaft 5 and attach the cap 22 to the upper end of the body member 21 by a threaded engagement 29 and pivotally attach the disc 23 to the top wall of the cap 22 by means of a pivot 30. The disc 23 and the top of the cap are provided with the same type of limit stop and projection respectively, as that shown in Figures 1 and 3. The pepper cylinder 24 is pressed into sealed engagement with the boss 28 and within the sealing ring 27 by the advancement of the cap 22 in its threaded engagement as at 29 with the threads on the interior of the body member.

While I have shown a particular form of embodiment of my invention, I am aware that many minor changes therein will readily suggest themselves to others skilled in the art, without departing from the spirit and scope of the invention. Having thus described the invention, what I claim as new and desire to protect by Letters Patent is:

A condiment dispenser comprising in combination, a hollow cylindrical body member closed at its bottom end by an integrally formed bottom wall having a centrally disposed upwardly extending boss formed thereon, said boss having an internally threaded vertical bore formed therein, a cylindrical cap closed at one of its ends and reduced in outside diameter at its opposite open end for a forced fit within the upper end of said cylindrical body member, a boss formed integral with and depending from the under side of said closed end of the cap, an upwardly extending boss formed on the top side of said closed end of the cap, each boss having an internally threaded vertical bore formed therein, a concentric retaining ring formed on the underside of said closed end of said cap, apertures formed through said

closed end of the cap, an apertured disc having a central opening formed therein by which said disc is rotatably mounted upon the closed end of the cap and about said last mentioned upwardly extending boss, a retaining screw secured within said internally threaded vertical bore in said upwardly extending boss for maintaining said disc in operative engagement with the closed end of said cap, a downwardly extending peripheral flange formed integral with said disc and surrounding said cylindrical cap, a cylinder of greater length than said cylindrical body member and having its lowermost end engaged with said boss formed on said bottom wall of said cylindrical body member and its opposite or upper end engaged within said retaining ring, a shaft threaded at both of its ends and engaged with the threaded bore in said depending boss and with the threaded bore in the boss on said bottom wall of said body member whereby said cap may be advanced on the threads on one end of said shaft for firmly engaging the cap with the cylindrical body member and said cylinder with said retaining ring and with the bottom wall of said cylindrical body member.

ROBERT C. GRAY.
